UNITED STATES PATENT OFFICE.

ENOCH RUTZLER, OF NEW YORK, N. Y.

PIPE-HANGER.

SPECIFICATION forming part of Letters Patent No. 443,198, dated December 23, 1890.

Application filed August 28, 1890. Serial No. 363,309. (No model.)

To all whom it may concern:

Be it known that I, ENOCH RUTZLER, of the city and county of New York, in the State of New York, have invented a new and useful Improvement in Pipe-Hangers, of which the following is a specification.

My invention relates to an improvement in pipe-hangers in which the hanger is formed in two half-sections and provision made for the seating therein of anti-friction devices to admit of the free longitudinal adjustment of the pipe within the hanger without liability of binding.

A practical embodiment of my invention is represented in the accompanying drawings, in which—

Figure 1 represents a hanger in elevation, looking in the direction of the line of pipe, showing the position of the section of pipe therein. Fig. 2 is a view of one of the half-sections of the hanger in detail. Fig. 3 is a view of the other half-section in detail. Fig. 4 is a transverse section taken through line xx of Fig. 1; and Fig. 5 is a top plan view of the lower portion of the hanger, showing the anti-friction rollers seated.

The half-sections of the hanger are denoted, respectively, by A and B. They are each provided with upwardly-extended neck portions a and b , which approach each other and are adapted to receive between them the depending tongue c of a fixed support C. The necks a and b are further provided with perforations a' and b' , through which and through a perforation in the tongue c a securing-bolt D is intended to pass. A nut d on the projecting end of the bolt D serves to lock the upper ends of the two half-sections to the depending tongue c . The middle portion of the sections A and B curve outwardly to surround the opposite sides of the pipe and then inwardly toward one another to extend underneath the pipe. Each of the sections A and B is extended past the lower middle portion of the pipe, so that the two half-sections when in position overlap each other for a considerable distance. The overlapping portion of the section A is represented by a^2 , and the overlapping portion of the section B is represented by b^2 . One of said overlapping portions, in

the present instance a^2 , is provided with laterally-extending rounded recesses a^3 , located preferably near each other and one upon each side of the vertical axis of the hanger. The lower edge of the portion a^2 on the side toward the overlapping portion b^2 is recessed, as shown at a^4 , to receive a corresponding projecting flange b^3 on the lower edge of the portion b^2 when the parts are assembled. The overlapping portion b^2 may be made with its inner face flat, as shown, and is intended to approach the portion a^2 to a point where it will securely lock the spherical balls or rollers E in their seats a^5 , with their upper faces projecting slightly above the upper edges of the overlapping portions $a^2 b^2$. The parts are assembled by placing the balls or rollers E in their seats a^5 , and then adjusting the overlapping portion b^2 in position with its projecting flange b^3 in the recess a^4 , and locking the two parts together by means of a bolt F, provided with a nut f, the bolt extending through registering perforations f' in the two overlapping portions.

As an additional locking device I provide the upper corner at the free end of the portion a^2 with a recess a^6 , in which fits a projecting lug b^4 upon the overlapping portion b^2 , and so prevents any liability of the free end of the portion a^2 becoming laterally displaced.

When the parts are adjusted, the pipe G rests upon the ball-rollers E, and may be readily adjusted to form the necessary connections.

Although I have herein shown two seats for the reception of two ball-bearings, it is evident that the number might be greater or less than two, if so desired.

What I claim as my invention, and desire to secure by Letters Patent, is—

1. A pipe-hanger comprising two overlapping sections, the overlapping portions extending beneath the position which the pipe is intended to occupy, an anti-friction device located between the overlapping portions of the sections, and means for securing the sections together, substantially as set forth.

2. A pipe-hanger comprising two overlapping sections, one of the sections being pro-

vided with rounded seats for the reception of ball-bearings, and the other section forming a guard to lock the bearings in their seats, and means for securing the sections together, substantially as set forth.

3. A pipe-hanger comprising two sections, the lower portions of the two sections overlapping each other below the position which the pipe is to occupy, a recess upon one of the sections and a corresponding tongue upon

the opposite section arranged to engage the recess, seats for the ball-bearings formed in one of the overlapping sections, and means for securing the sections together, substantially as set forth.

ENOCH RUTZLER.
